Des. 208,862
Patented Oct. 10, 1967

208,862

ELECTRON DISCHARGE DEVICE

Benjamin V. Valles, San Jose, Calif., assignor to Litton Precision Products, Inc., San Carlos, Calif., a corporation of Delaware

Filed Aug. 18, 1966, Ser. No. 3,529

Term of patent 14 years

(Cl. D26—8)

FIGURE 1 is a front elevational view of the electron discharge device.

FIGURE 2 is a top view of the electron discharge device.

FIGURE 3 is a bottom view of the electron discharge device.

FIGURE 4 is a fragmentary side view of a stem of the electron discharge device as seen along the lines 4—4 of FIGURE 1.

I claim:

The ornamental design for an electron discharge device, substantially as shown.
